CLAIM

The ornamental design for an overlay frame for tight-flask molding machine, as shown and described.

DESCRIPTION

FIG. 1 is a top perspective view of an overlay frame for tight-flask molding machine of the present invention.

FIG. 2 is a bottom perspective view of the overlay frame for tight-flask molding machine of FIG. 1.

FIG. 3 is a front view of the overlay frame for tight-flask molding machine of FIG. 1.

FIG. 4 is a rear view of the overlay frame for tight-flask molding machine of FIG. 1.

FIG. 5 is a top plan view of the overlay frame for tight-flask molding machine of FIG. 1.

FIG. 6 is a bottom view of the overlay frame for tight-flask molding machine of FIG. 1.

FIG. 7 is a right side view of the overlay frame for tight-flask molding machine of FIG. 1.

FIG. 8 is a left side view of the overlay frame for tight-flask molding machine of FIG. 1; and,

FIG. 9 is an enlarged sectional view taken along the line 9-9 of the overlay frame for tight-flask molding machine of FIG. 3.

The features shown in broken lines illustrate portions of the overlay frame for tight-flask molding machine and form no part of the claimed design.
